UNITED STATES PATENT OFFICE.

ELMER ELSWORTH MACK, OF FORT SCOTT, KANSAS.

AUTOMOBILE-LOCK.

1,282,898.

Specification of Letters Patent. Patented Oct. 29, 1918.

Application filed April 17, 1918. Serial No. 229,133.

To all whom it may concern:

Be it known that I, ELMER E. MACK, a citizen of the United States, residing at Fort Scott, in the county of Bourbon and State of Kansas, have invented a new and useful Automobile-Lock, of which the following is a specification.

The subject of the present invention is a lock intended for locking an automobile 10 against unauthorized use.

The main object of the invention is to provide means for locking the gasoline control lever so that fuel may not be fed to the cylinder.

15 A further object contemplated by the invention is the production of a lock which may not be easily picked.

A still further object of the invention is the production of a lock admitting of a 20 great variety of variation in the key hole and key so that the key of one lock may not be used for opening another.

The invention also contemplates the provision of a simple, durable and efficient lock.

25 With the foregoing and other objects in view which will appear as the description proceeds, the invention resides in the combination and arrangement of parts and in the details of construction hereinafter described 30 and claimed, it being understood that changes in the precise embodiment of the invention herein disclosed can be made within the scope of what is claimed without departing from the spirit of the invention.

35 One practical embodiment of the invention is shown in the accompanying drawing, wherein:—

Figure 1 is a plan view of a steering wheel with a lock constructed in accordance with 40 the invention in place thereon;

Fig. 2 is a side elevation of the lock with a fragment of the steering post to which it is attached shown;

Fig. 3 is a view in side elevation of the lock 45 with the casing in section, the key shown in place with a part broken away;

Fig. 4 is a rear elevation of the lock with the casing in section;

Fig. 5 is a fragmentary view in perspective of the key and mechanism operated thereby;

Fig. 6 is a fragmentary view in perspective of the key in section and the key receiving pin.

55 Referring to the drawing by numerals of reference:—

In carrying out the invention a suitable housing is provided which consists of a base 1 upon which is mounted a cover 2. The cover 2 is provided in its upper end with a slot 3 through which the lock bolt passes and with a key hole 4, while in one side wall it is provided with a vertically disposed slot 5.

Secured to and rising from the base 1 are the guide strips 6 in which slide the lock bolt 7, the bolt being bifurcated at its outer end as indicated at 8, to straddle the gasoline lever 9 of an automobile. An offset 10 is provided in the guideway formed by the guides 6 and within this offset normally rest the vertically disposed arms 11 of bell crank levers which are pivoted or fulcrumed on a horizontal shaft 12 which extends transversely of the lock and is supported in the offset portion of the guides 6. The arms 11 have their free ends bent or angled as at 11' and these ends rest against the face of the bolt 7 when the bolt is in lowered or unlocked position, and take under the inner end of the bolt when the bolt is in extended 80 or locked position to retain the bolt in such extended position.

The other arms 11'' of the bell crank levers are contacted by fingers 13 which are seatable downwardly upon said arms and which fingers extend from and are carried by rods 14 slidable in grooves 15 which are formed in and extending longitudinally of a pin 15'. The pin 15' is secured to and rises from the base 1. The grooves 15 are adapted 90 to receive lugs 16 which are secured to and extend inwardly from the inner walls of the barrel of the key 17. The grooves 15 are offset, as seen in Fig. 6, so that when the key is inserted into the lock it must be given a 95 partial turn to bring the lugs 16 into contact with the rods 14.

A vertically disposed rod 18 may also be provided in the lock, adjacent the pin 15' and this rod is preferably formed with an angled lower end 19, though the same is not a necessary part thereof, and an angled upper end 20. The rod 18 is mounted to slide up and down through a guide plate 21 with its lower end in contact with the arm 11a of the central lever 11. The upper end 20 of the rod 18 is in position to be contacted by the lug 17' of the key 17 when the key is in position to contact the rods 14 with its lugs 16.

105 Springs 23 are secured to the base 1 in any suitable manner and their ends underlie the 110

arms 11" and 11^a of the levers 11 to retain the parts in elevated positions.

The shank of a knob or button 26 extends through the slot 5 and is secured in any suitable manner to the bolt 7 so that the bolt may be raised or lowered by raising or lowering the knob 26. A strap 24 or like supporting means is secured to the cover 2 and is adapted to encircle the steering post 25 of an automobile to which it is clamped by bolts or otherwise.

It will be evident that the bolt 7 may be extended so that its bifurcated end will straddle the lever 9 by drawing the knob or button 26 upwardly. When this is done, the ends 11' of the lever arms 11 will spring below the bolt 7 under the force of the springs 23 and so lock the bolt in its extended position. To now return the bolt and release the lever it will be necessary to use the key 17.

The key 17 is inserted through the key hole 4, the pin 15' entering the barrel of the key and the lugs 16 entering the groove 15. When the key has been inserted to the offset 25 of the groove 15 it becomes necessary to give the key a partial turn to bring the same in register with the rods 14 so that they may be depressed and the bell crank levers rocked to bring the ends of the arms 11 from beneath the bolt 7. This releases the bolt and allows it to be drawn from contact with the lever 9 and into the casing.

As heretofore explained, when the key is turned to bring the lugs 16 into contact with the rods 14 the lug 17' is in position to contact the rod 18 and so depress its arm 11" of the bell crank lever.

From the foregoing it will be apparent that changes in the formation of the key

hole slot may be resorted to in order to prevent one key opening several locks, and also changes in the location or spacing of the grooves 15, thus rendering a great variety of changes possible without an apparent change in the lock.

Having thus described the invention, what is claimed as new and sought by Letters Patent, is:—

1. An automobile lock including a casing, a bolt slidable within the casing, means for sliding the bolt to extended position, bell-crank levers within the casing released by the extension of the bolt to lock the bolt in extended position, rods mounted to slide in the casing and contacting the bell-crank levers, and means for sliding the rods to rock the levers and release the bolt for retraction.

2. An automobile lock including a casing, a bolt slidable within the casing, means for sliding the bolt to extended position, means within the casing released by the extension of the bolt to lock the bolt in extended position, a pin in the casing provided with grooves, rods slidable in the grooves and contacting the bolt locking means, and a key adapted to fit over the pin and having lugs adapted to the grooves to contact the rods and actuate the bolt locking means to release the bolt for retraction.

In testimony that I claim the foregoing as my own, I have hereto affixed my signature in the presence of two witnesses.

ELMER ELSWORTH MACK.

Witnesses:

Mrs. G. C. PRIESTLEY,
Mrs. GRACE MACK.
